UNITED STATES PATENT OFFICE.

JAMES LEONARD CAMPBELL, OF BARRYTON, MICHIGAN.

CIRCUIT-COMPLETING PLUG FOR LAMP-SOCKETS.

1,230,826.

Specification of Letters Patent. Patented June 19, 1917.

Application filed April 5, 1916. Serial No. 89,041.

To all whom it may concern:

Be it known that I, JAMES LEONARD CAMPBELL, a citizen of the United States, and a resident of Barryton, in the county 5 of Mecosta and State of Michigan, have invented a new and Improved Circuit-Completing Plug for Lamp-Sockets, of which the following is a full, clear, and exact description.

10 This invention relates to an attachment for lamp sockets of lighting systems in which lamps are in series, whereby the burnt-out or broken lamp can be removed and the attachment plugged into the empty 15 socket so as to complete the circuit and thus take the place of the lamp.

The invention is especially adapted for electric lighting systems on automobiles wherein the lamps are in series.

20 The invention has for its general object to provide an attachment of the class described which is of comparatively simple and inexpensive construction, reliable and efficient in use, and so designed that it can 25 readily replace a defective lamp, in a series wired electrical system, to thereby permit the use of a part of the system until replacement can be made of the defective lamp, thus enabling an automobilist to 30 travel with one or more lamps burning until the point is reached where replacement of the defective lamp can be made, the attachment being in the nature of a plug having suitably arranged contact or contacts so as 35 to complete the circuit when inserted in a lamp socket.

With such objects in view, and others which will appear as the description proceeds, the invention comprises various novel 40 features of construction and arrangement of parts which will be set forth with particularity in the following description and claim appended hereto.

In the accompanying drawing, which 45 illustrates certain embodiments of the invention and wherein similar characters of reference indicate corresponding parts in all the views,

Figure 1 is a diagrammatic view of a 50 lighting system with the plug inserted in one of the lamp sockets to complete the circuit; and

Fig. 2 is an enlarged sectional view of one of the sockets with the plug in position.

55

Referring to the drawing, A and A' designate lamp sockets in the lighting circuit B, and in one of the sockets is a circuit-completing plug or attachment C, while in the other is a lamp D. The attachment C is 60 a plug, the body of which is made of insulating material and has extending from one end a central contact 2 which is held in place by being anchored in the insulation 1. Projecting from opposite sides of the body 65 1 are pin-like members 4 which are insulated from the contact 2, and these members 4 are adapted to engage in bayonet slots 5 in the shells 6 of the sockets A and A'. In the sockets are contacts 7 and 8 which are 70 adapted to engage the terminals 9 and 10 of the lamps. When a lamp burns out the attachment C is inserted in the socket and the contact 2 thereof engages both contacts 7 and 8, so that the lighting circuit will be 75 completed with only one lamp in service.

Having thus described my invention, I claim as new and desire to secure by Letters Patent:

The combination of a lighting circuit including a plurality of lamp sockets having a plurality of contacts therein and having bayonet slots in the walls of the socket, with a circuit-closing plug comprising a body of insulation, a bridging contact anchored 85 therein for engaging the contacts on the lamp socket for electrically connecting them, and pins anchored in the body of insulation and separated from the said contact therein, said pins being engageable in the 90 bayonet slots to hold the contact of the plug in engagement with the contacts of the socket.

In testimony whereof I have signed my name to this specification in the presence of 95 the subscribing witnesses.

JAMES LEONARD CAMPBELL.
